(57) **CLAIM**

The ornamental design for a base for a warning light, as shown and described.

DESCRIPTION

FIG. 1 is a perspective view of a base for warning light, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom view thereof; and,

FIG. 8 is another perspective view of FIG. 1, wherein the broken-line showing of a dome lens is for illustrative purposes only, and forms no part of the claimed design.
